UNITED STATES PATENT OFFICE.

DONALD E. AGNEW, OF PORTLAND, OREGON, ASSIGNOR OF ONE-HALF TO HERBERT F. SULLIVAN, OF PORTLAND, OREGON.

DETACHABLE-RIM CLAMP.

1,191,101.

Specification of Letters Patent. Patented July 11, 1916.

Application filed January 13, 1916. Serial No. 71,911.

To all whom it may concern:

Be it known that I, DONALD E. AGNEW, a citizen of the United States, residing in the city of Portland, county of Multnomah, and State of Oregon, have invented certain new and useful Improvements in Detachable-Rim Clamps, of which the following is a specification.

My invention relates to detachable rim clamps, such as are used for securing a detachable rim in place upon a wheel and at the same time wedging between the wheel felly, or felly band, and a detachable rim, for the purpose of preventing any looseness therein.

The principal object of my invention is to provide such a clamping, or fastening, device which is capable of certain expansion, or contraction, in order that it may be more readily fitted to the space between the detachable rim and the felly band.

In order that others may clearly understand my invention, I have illustrated the preferred form thereof in the accompanying sheet of drawings, which I will now describe.

Figure 1 is a face view of the device; Fig. 2 is an edge view thereof; Fig. 3 is a top plan view of the lower portion of the device, with the upper portion thereof removed; and Fig. 4 is a sectional view through a wheel felly and tire, showing my invention in use.

Referring now more in detail to the drawings, my detachable rim clamp comprises a body 1, with a head, or bill-like, portion 2, the body having a bolt hole 3 therethrough, by means of which it is secured in place as hereinafter referred to, and the head, or bill-like, portion 2 is provided in its top surface with a series of teeth, or notches, as 4, extending across the same in a direction parallel with the plane of the body 1, and also provided with a transversely extending groove 5, clearly shown in top plan view, Fig. 3. The top, or upper portion, 6, of my clamp, is provided with corresponding notches, or teeth, on its under side, as clearly indicated, adapted to fit into the notches 4, in the top surface of the main portion of the device. Said top is also provided with a transversely extending rib 7, adapted to fit into groove 5, in the manner clearly indicated in Fig. 1. The object of this interfit between the groove 5 and the rib 7, is to prevent the top from any relative movement

laterally of said device which would be longitudinally of the teeth, or notches, 4. The teeth, or notches, 4, prevent any movement relatively in the opposite direction of said top member. The head and bill-like portion 2, of the main member 1, is wedge form, as is also the top, whereupon if the top member be adjusted inwardly, as indicated in dotted lines, Fig. 2, the thickness of the wedging portion which fits between the detachable rim 8, and the felly band 9, is increased, and if said top member 6, is adjusted in the opposite direction one notch, or more, the thickness of the wedging portion of the device is reduced.

The device is put into place, as indicated in Fig. 4, the bolt 10 of the felly passing through the hole 3, in the body member 1. As a rule, these clamp devices are spaced apart around the outside of the wheel rim in sufficient number to securely hold a detachable rim in place.

Thus it will be seen that I have provided a combination clamp and wedging device which is capable of certain adjustments, whereby to make possible a better fit of the device between the detachable rim 8, and the felly band 9. It is also possible many times to use my improved adjustable clamping device, where a similar device made in one piece would be too large, or too small to serve the purpose for which it is intended.

I am aware that changes can be made in the form of my device without departing from the spirit thereof, and I do not, therefore, limit the invention to the particular form here shown, except as I may be limited by the hereto appended claims.

I claim:

1. A clamping device of the character shown and described, comprising a body portion provided with a wedging portion adapted to be inserted underneath a detachable wheel rim, and a top portion adjustable thereon, whereby to increase or diminish the thickness of the portion inserted under said wheel rim.
2. A clamping device of the character referred to adapted for use with a detachable wheel rim, which clamping device has a two-part wedging portion, the parts of which are adjustable relative to each other, whereby to change the thickness of the wedging portion of said device, and means for securing said device in place.

3. In combination with a wheel rim and a detachable rim, a clamping device having a two-part wedging portion adapted to be inserted therebetween, the parts of which are 5 adjustable relative to each other, whereby to increase, or diminish, the thickness thereof, and means for securing said clamping device in place.
4. A demountable rim clamp of the character shown and described, comprising a body having a head of tapering form and provided in its upper face with notches, a top member of tapering form provided in its under side with notches adapted to mesh 10 with the notches in said head, whereby as said top portion is adjusted in opposite directions relative to said head, the thickness of the wedging portion of said clamp is increased, or diminished, substantially as and 15 for the purpose described.
5. In combination with a wheel rim and a demountable rim adapted therefor, a clamping device having a body with means for securing it to said wheel rim and having 20 a head of tapering form adapted to be inserted between said wheel rim and said detachable rim, a top member adjustably mounted upon said head and having interfitting connections therewith to prevent 25 movement relative thereto, said top member being adapted to increase or diminish the thickness of the portion of said head between said wheel rim and said detachable rim as it is adjusted in one direction or the other relative to said head, substantially as 30 described.
6. In combination with a wheel rim and a detachable rim therefor, a clamping device comprising a body having means for securing it to the side of said wheel rim, and having a head of tapering form provided in its upper surface with notches, a top, or cap, member having in its under side corresponding notches adapted to mesh with the notches in said head, whereby to be adjusted 35 to different positions thereon to increase or diminish the thickness of said head, one of said parts being provided with a transversely extending groove and the other being provided with a transversely extending rib adapted to fit into said groove, whereby to prevent sliding movement of one part relative to the other, substantially as 40 and for the purpose described.

Signed at Portland, Multnomah county, Oregon, this 7th day of January, 1916.

DONALD E. AGNEW.

In the presence of—

I. M. GRIFFIN,

J. C. STRENG.
